PROCESS FOR TREATING PETROLEUM OIL

Filed July 31, 1922

UNITED STATES PATENT OFFICE

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA

PROCESS FOR TREATING PETROLEUM OIL

Application filed July 31, 1922. Serial No. 578,703.

This invention relates to improvements in process and apparatus for treating petroleum oil and refers more particularly to a cracking process for the conversion of relatively high boiling point hydro-carbons into hydro-carbons having a relatively lower boiling point. The process is preferably operated continuously and under a substantial pressure of the generated vapor. Among 10 the salient objects of the invention are to provide a process in which the oil is heated to a cracking temperature and passed successively through a series of vaporizing chambers which are connected so that the 15 vapor pressures in the successive chambers may be accurately controlled and the liquid oil passing therethrough may be regulated to recycle the residual products or divert the residual products, as desired.

20 The single figure is a diagrammatic side elevational view of an apparatus suitable for carrying out the invention.

Referring in detail to the drawing, 1 is a storage tank which is connected by means 25 of a line 2 in which is interposed a pump 3 and valve 4, to the heating coil 5 mounted in a furnace 6, the latter being heated by means of gas burner 7'. The heating coil 5 is connected to a vaporizing chamber 6, 30 which is in turn serially connected to succeeding chambers 7, 8 and 9 by vapor pipes 10, 11 and 12 and liquid connections 13, 14 and 15 respectively. The vapor lines 10, 11 and 12 are controlled by valves 16, 17 and 18, while the liquid lines 13, 14 and 15 are regulated by the valves 19, 20 and 21. Each 35 of the chambers 6, 7, 8 and 9 have residuum draw-off lines 22 controlled by valves 23, which communicate with a single header 24, 40 which serves to return the residual products to the storage tank 1. Each of the residuum lines has a secondary connection 25 controlled by valves 26, by means of which the residual oil may be diverted from the residuum lines to separate storage not shown. Beneath the chambers 6 and 7 are provided 45 burners 27, by means of which the temperatures in the chambers 6 and 7 may be increased as desired. From the top of the 50 chamber 9 there is a vapor line connection 28

controlled by valve 29 to a refluxing or dephlegmating tower 30. The dephlegmator in turn is connected by gooseneck 31, regulated by valve 32, to the water condenser 33, the discharge end of the condenser coil being 55 connected by means of a line 34, controlled by a valve 35, to the receiving tank 36, the latter being equipped with a liquid draw-off valve 37, a pressure relief valve 38, a pressure gauge 39 and a liquid level gauge 40. 60 From the bottom of the dephlegmator a draw-off line 41, in which is interposed a valve 42, communicates with a storage tank 1, by means of which the liquid reflux condensate separated from the vapor in the dephlegmating zone may be returned to the storage tank and recycled with the raw oil or charging stock to the heating coils to be 65 retreated.

In operation, the oil from the storage tank 70 is charged by means of the pump 3 through the line 2 to the heating coil 5 and while circulating therethrough is raised to a conversion temperature. In this condition it is introduced to the initial chamber 6 of 75 the battery of vaporizing chambers, where a portion of the volatile products will pass off through the line 10 to the succeeding chamber 7. In a like manner the liquid products, if the valve 19 be open, will overflow 80 into the chamber 7 and into the succeeding chambers in a similar manner. Thus in each successive stage the oil will have ample opportunity to become completely digested or assume an equilibrium where- 85 by the volatile products are separated from the higher boiling point liquid residual substances which are drawn off through the residuum lines 22 and returned through the header 24 to the storage tank. In the initial 90 stages of operation it is desirable to recycle substantially all of the residual products, as they are very little carbon laden and do not add appreciable quantities of free carbon to the charging stock. As the process proceeds and the residual oils become heavier and contain more free carbon, it is advisable to by-pass the heavier products and recycle only the relatively carbon-free oils. In order 95 to produce this effect of diverting the 100

heavier residual substances, the valve 19 is closed. Thus the heavier oils will collect in the initial stage and may be drawn off through the line 25 tapped into the residual draw-off line 22 of the chamber 6. This will necessitate the valve 23 being closed and the valve 26 being open. In a similar manner, after the heavier oil has collected to a height so that it will overflow into the chamber 7, the valve 20 may be closed and the residual products isolated in the two tanks 6 and 7, and in a like manner the succeeding tanks may be used to collect the heavier residual oils while only the lighter reflux 15 and relatively light residual substances are recycled to the storage tank to be returned with the charging stock. It will be noted by operating the process in this manner that the apparatus may be run continuously 20 for a much greater period of time, it being only necessary to keep the residuum lines from the chambers containing the heavier oils clear in order to divert the carbon laden products. Burners are supplied 25 under the tanks 6 and 7 in order to add additional heat to the oil contained in these chambers, so as to promote the reaction taking place and increase the volume of vapors evolved from the oil in these initial 30 stages. The size of the dephlegmator will necessarily have to be increased in order to supply sufficient dephlegmation to the vapors evolved in the various chambers. In place of the four tanks shown, additional 35 tanks may be connected without departing from the scope of the invention. The features of recycling the unvaporized products from the conversion chambers and providing means for isolating and diverting the heavier substances and at the same time 40 recycling selected portions which are but lightly carbon laden, together with further advantages of continued operation over long periods of time and the accuracy of control 45 which may be had over the apparatus, are factors of importance in connection with the process.

By treating mid-continent gas oil of approximately 32° Baumé gravity at temperatures ranging from 600 to 900° F. and passing them through vapor chambers serially connected as explained, I have been able to procure a substantial yield of high quality distillate having gravities of from 55 48 to 52° Baumé and comprising from 40% to 60% of the oil treated.

I claim as my invention:

1. A process for treating petroleum oil consisting in raising the oil to a conversion 60 temperature in a cracking zone, passing the oil through successive vapor chambers in maintaining a superatmospheric pressure on the oil in said chambers, withdrawing the evolved vapors therefrom and subjecting 65 them to a dephlegmating action, condensing

the dephlegmated vapors and recycling the unvaporized oil from selected vapor chambers to the cracking zone for retreatment, and withdrawing the unvaporized oil from the remaining vapor chambers from the system without returning the same to said cracking coil for further cracking. 70

2. A process for treating petroleum oil, consisting in passing a stream of oil through a cracking coil where said oil is subjected 75 to a cracking temperature, in passing the highly heated oil through successively arranged vapor chambers, in causing the oil to accumulate in a pool in each chamber, in maintaining a superatmospheric pressure on 80 the oil in each chamber, in applying heat to at least one of the first chambers of the series without applying heat to advanced chambers of the series, in subjecting the vapors to a reflux condensing action, in withdrawing a regulated quantity of unvaporized oil from a selected vapor chamber, and in 85 recycling said oil through said cracking coil for further cracking.

3. A process for treating petroleum oil, 90 consisting in passing a stream of oil through a cracking coil where said oil is subjected to a cracking temperature, in passing the highly heated oil through successively arranged vapor chambers, in causing the oil 95 to accumulate in a pool in each chamber, in maintaining a superatmospheric pressure on the oil in each chamber, in applying heat to at least one of the first chambers of the series without applying heat to advanced chambers of the series, in subjecting the vapors to a reflux condensing action, in withdrawing a regulated quantity of unvaporized oil from a selected vapor chamber, in mixing 100 said oil with said reflux condensate, and in 105 returning said mixed oil to said cracking coil for further cracking.

4. A continuous process for cracking hydrocarbon oil, consisting in initially raising the oil to a cracking temperature, while 110 flowing in a stream through a heating zone, in thence delivering the heated oil to the first of a series of reaction chambers through which the oil successively flows, in taking off vaporous constituents from said reaction 115 chambers for condensation and collection, in the early stages of the process removing from the first chamber of the series heavy unvaporized oil collecting therein, without again returning the same to said heating zone, while simultaneously returning the lighter unvaporized oil from the remaining 120 chambers of the series to said heating zone for further treatment, and in a more advanced stage of the process removing the 125 heavy unvaporized oil from a succeeding chamber of the series without returning the same to said heating zone.

5. A process for cracking hydrocarbon oil, consisting in circulating the oil in a cycle, in 130

one portion of which the oil passes in a restricted stream through a heating zone and is raised to a cracking temperature, and in another portion of which the oil successively flows through a series of reaction chambers, in initially circulating all of the unvaporized oil from said chambers through said heating zone, in thereafter, during the early stages of the process, removing heavy unvaporized oil collecting in the first chamber of the series from the cycle, while simultaneously recirculating the light unvaporized oil from the remaining chambers of the series, and in a more advanced stage of the process removing the heavy unvaporized oil from a succeeding reaction chamber of the series, and in continuously taking off vapors evolved from the oil in said reaction chambers for condensation and collection.
